BROODER

William R. Hartung, Des Moines, Iowa

Application November 12, 1931
Serial No. 574,551

5 Claims. (Cl. 119—32)

The object of my invention is to provide a brooder of simple, durable and inexpensive construction so arranged and combined that a water container is located close to the floor to permit chicks to pass under it, and so arranged that the water in the container may be thermostatically controlled to maintain a predetermined degree of heat, and that the air surrounding the water container may be thermostatically controlled to maintain a different predetermined amount of heat.

A further object is to provide a brooder of this character in which, from a single down-draft burner, the products of combustion may be passed through or in close contact with the water to heat it, or it may be passed by the more direct route to the flue so that a different proportion of the heat from the burner may be applied to the air surrounding the water container.

20 A further object is to provide thermostatically controlled means whereby the temperature of the water in the container may be thermostatically controlled by the admission of cold water.

25 My invention consists in the construction, arrangement and combination of the various parts of the device, whereby the objects contemplated are attained, as hereinafter more fully set forth, pointed out in my claims, and illustrated in the accompanying drawing, in which:

30 Figure 1 shows a vertical, central, transverse, sectional view of a brooder embodying my invention.

Figure 2 shows a similar view taken at right angles to that shown in Figure 1.

35 Figure 3 shows a horizontal sectional view on the line 3—3 of Figure 2.

Figure 4 shows a similar sectional view on the line 4—4 of Figure 2.

40 Figure 5 shows a detail view partly in section illustrating the float controlled valve for the admission of cold water into the water container; and

Figure 6 shows a detail end view illustrating the float and its controlling lever.

45 Referring to the accompanying drawing, I have used the reference numeral 10 to indicate a water container or pan, supported on legs 11 spaced apart from the floor far enough to permit chicks to enter under it. These legs are preferably adjustable so that the height of the water container from the floor may be regulated as desired.

50 A cold water pipe 12 enters the pan through a ball valve 13 of ordinary construction, specifically shown in Figure 5, and this ball valve is controlled by a float 14 of ordinary construction,

the parts being so arranged that when the float moves upwardly toward a horizontal position, the ball valve is closed, and when the float moves downwardly to the position shown in Figure 5, the ball valve is open to permit the flow of cold water into the water container. There is also a water overflow pipe 15.

Mounted within the water pan is a thermostat device 16 of ordinary construction connected to a lever 17, which lever is also extended over the float valve 14. These parts are so arranged that when the thermostat device 16 expands, due to excessive heat of the water, the float is pulled downwardly and cold water admitted into the container.

55 The heater body is indicated generally by the reference numeral 18 and is provided with a central cylindrical air inlet flue 19, and a discharge flue 20. A horizontally arranged partition 21 divides the body into upper and lower sections, and the lower section is provided with deflector walls 22 substantially U-shaped and extending from the down-draft flue 19 to a point spaced apart from the adjacent side of the body, as shown in Figure 4, and the products of combustion pass around the interior of the under section of the body to the openings 23 in the horizontal partition 21, and then pass upwardly and forwardly, being directed by the upright partitions 25 through the opposite side of the body, and then they move toward each other and across the central portion of the upper compartment of the body to the discharge flue 20.

60 This entire arrangement of the various passageways within the body is simply for the purpose of causing the products of combustion to have a fairly long travel before passing to the flue, so as to retard the maximum amount of heat from the products of combustion before passing to the flue.

65 When starting the oil burner it is desirable to have a short direct passageway to the flue, and for that purpose I have provided an opening in the inlet flue 19 close to the flue 20, which opening is normally closed by a slide valve 20a controlled by a handle 20b.

70 Mounted within the lower end of the down-draft flue 19 is an oil burner device, indicated generally by the reference numeral 26. This burner is made the subject matter of a co-pending application of mine, filed February 9, 1931, Serial Number 514,527, and is not herein specifically illustrated or described, but for the purpose of this application may be considered simply as a down-draft oil burner.

The said body 18 is preferably supported upon a circular rim 27 fixed to the body and extended downwardly and resting upon the bottom of the water container 10. Water circulating openings 5 28 are formed in this circular rim 27.

A fuel supply pipe for oil leads to the burner and is indicated by the reference numeral 29, and is in communication with a regulating valve 30 of ordinary construction, controlled by a lever 10 31, which lever is automatically controlled by a thermostat device 32 in the air surrounding the water container.

In a brooder it is desirable that a place be provided where chicks may enter, and which 15 space will be constantly heated to a temperature of about 105° F. It is also desirable that the air surrounding this space be constantly maintained at a temperature of about 85° F. and for the purpose of constantly providing these two different 20 temperatures, regardless of the atmospheric conditions to which the brooder is subjected at times, I have provided the following mechanism.

In the bottom of the body 18 I provide a pipe 33, one end opening into the passageway between 25 the walls 22 and then extended downwardly through the water into the water container and having its upper end extended upwardly through the bottom of the body 18 into the interior of the lower compartment of said body, as clearly shown 30 in Figure 1, and immediately above the inlet opening of this pipe 33 is a valve 34 connected to the rod 35, which rod is connected at its upper end to a lever 36, and this lever is connected by a rod 37 with a thermostat device 38 located in 35 the water in the container.

These parts are so arranged that when the water in the container is heated beyond a certain 40 predetermined degree the thermostat device 38 expands and pushes the valve 34 downwardly parallel with the bottom of the body 18, closing the passageway through the pipe 33, so that all of 45 the products of combustion pass through the body 18. The major portion of the heat from the burner serves to heat the air surrounding the water container.

When, however, the temperature of the water in the container falls below the predetermined amount, the thermostat device 38 contracts and 50 opens the valve 34 to the position shown in Figure 1, and causes the major portion of the products of combustion from the burner to be deflected downwardly through the pipe 33, so that its heat is applied directly to the water, and the temperature of the water is quickly raised to the desired 55 point without having so much of the heat from the burner applied to the air surrounding the body 18.

A hover 39 may be applied above the body 18, if desired.

In practical use the amount of fuel applied to the down-draft burner is thermostatically controlled in the ordinary way, thus controlling the size of the flame from the burner. When starting 60 the brooder, and assuming that the water is cold, the valve 34 will be in its upwardly inclined position and will direct the major portion of the products of combustion through the pipe 33, and thus quickly bring the temperature of the water up to the desired point. When this has been reached 65 the valve 34 is automatically closed and the major portion of the products of combustion heat the surrounding air by radiation from the body 18, and when the temperature surrounding the air reaches a certain predetermined amount, it is 70 regulated by the thermostat device which auto-

matically controls the supply of fuel to the burner.

In the event that the water in the container should at any time exceed the predetermined degree of heat, it is automatically cooled to the desired point by the thermostat device 16 operating 80 the float 14 to admit cold water.

By this arrangement it will be seen that I have provided a brooder of very simple and inexpensive construction in which the water in the water container may be constantly maintained at a relatively high temperature, and that the air surrounding the water pan may at the same time be constantly maintained at a much less temperature, and that there are no rapidly flowing currents of air either in the space under the water container or in the space surrounding the body 18.

I claim as my invention:

1. In a brooder, the combination of a water pan supported in position to permit chicks to enter under and close to its bottom, a single heater for heating the water in the pan and the air surrounding the pan, an automatic thermostat device operated by the temperature of the water in the pan for controlling the amount of heat applied to the water from the heater, and a second 95 automatic thermostat device operated by the temperature of the air surrounding the water pan for controlling the amount of heat from the heater to be radiated into the air surrounding 100 the water pan, 105

2. In a brooder, the combination of a water pan supported in position to permit chicks to enter under and close to its bottom, means for heating the water in the water pan and the air surrounding the water pan, thermostatically controlled 110 means governed by the temperature of the water in the pan for regulating the amount of heat applied to the water in the pan, and a second thermostatically operated means governed by the temperature of the surrounding air for controlling 115 the amount of heat from the heating means to be applied to the surrounding air.

3. In a brooder, the combination of a water pan supported in position to permit chicks to enter under and close to its bottom, means for heating the water in the water pan and the air surrounding the water pan, thermostatically controlled means governed by the temperature of the water in the pan for regulating the amount of heat applied to the water in the pan, a second 125 thermostatically operated means governed by the temperature of the surrounding air for controlling the amount of heat from the heating means to be applied to the surrounding air, and thermostatically controlled means governed by the temperature of the water in the water pan for admitting cool water into the water pan. 130

4. In a brooder, the combination of a water pan supported in position to permit chicks to enter under and close to its bottom, means for heating the water in the water pan and the air surrounding the water pan, thermostatically controlled means governed by the temperature of the water in the pan for regulating the amount of heat applied to the water in the pan, a second thermostatically operated means governed by the temperature of the surrounding air for controlling the amount of heat from the heating means to be applied to the surrounding air, a source of water supply for the water pan, float controlled means for regulating the amount of water admitted into the water pan for maintaining a predetermined water level, and thermostatically controlled means governed by the temperature of the water in the water pan for operating said float con- 145 150

trolled means for admitting cool water to the water pan.

5. A brooder comprising a water container, means for supporting it in an elevated position whereby chicks may pass under it, a heater body above the water container, a burner within the body, means for conducting products of combus-

tion from the burner through the heater body to a flue, means for conducting products of combustion from the burner downwardly into the water container, and means for controlling the passage of the products of combustion through said conducting means. 80
